UNITED STATES PATENT OFFICE.

CHARLES ABEL, OF FORT SAM HOUSTON, TEXAS.

ROTARY TOOTH-BRUSH.

1,297,771.

Specification of Letters Patent. Patented Mar. 18, 1919.

Application filed October 8, 1918. Serial No. 257,358.

To all whom it may concern:

Be it known that I, LIEUT. COL. CHARLES ABEL, a citizen of the United States, residing at Fort Sam Houston, in the county of Bexar and State of Texas, have invented 5 new and useful Improvements in Rotary Tooth-Brushes, of which the following is a specification.

This invention relates to brushes, particularly to those of the rotary type, and has for its object the provision of a tooth brush comprising a casing having formed integrally upon one end thereof an open sided guard member within which is rotatably mounted a brush head protruding beyond the open side thereof and driven by an operating shaft rotatable through said casing and provided at its extremity with a crank handle, the construction and arrangement 20 of the brush being such that when placed in the mouth of the user a thorough cleansing action may be effected longitudinally of the teeth instead of transversely thereof so that particles of food may be easily removed 25 from the crevices between the teeth and brushed away from the gums, the guard member engaging against the cheek so as to prevent abrasion or laceration thereof.

An important object is the provision of a device of this character which is so constructed that the parts thereof may be readily dis-assembled to facilitate cleaning or to permit replacing of the brush head after it has become worn.

Another object is the provision of a device of this character which will be simple and inexpensive in manufacture, which may be readily operated, which will be efficient in use, durable in service and a general improvement in the art.

With the above and other objects and advantages in view the invention consists in the details of construction to be hereinafter more fully described and claimed, and illustrated in the accompanying drawing in which:—

Figure 1 is a side elevation of the complete device

Fig. 2 is a longitudinal sectional view therethrough

Fig. 3 is a detail cross sectional view through the guard member and brush head and

Fig. 4 is a detail view of the attaching 55 end of the brush and

Fig. 5 is a detail view of the brush engaging end of the operating shaft.

Referring more particularly to the drawings the numeral 10 designates the main or body portion of my device which is formed as a cylindrical casing which is cut away 60 along one side as shown at 11 to provide a substantially semi-cylindrical guard 12 the free end of which is provided with a bearing plate 13. Disposed within the casing 65 10 adjacent the cut away portion 11 is a partition 14 having a hole 15 formed centrally therein

The operating shaft is designated by the numeral 16 and is formed as a cylindrical member having one end reduced as shown at 17 for passage through the hole 15 in the partition 14 and which is provided adjacent its other end with a reduced portion 18 engageable within a hole 19 formed in a plug 75 20 externally threaded for engagement with the internally threaded open end of the casing 10. From this construction it will be seen that the operating shaft 16 may be rotated freely within the casing 10 but is 80 prevented from longitudinal movement by virtue of the partition 14 and plug 20. Adjacent the reduced portion 18, the operating shaft has formed thereon a crank handle 21 whereby the operating shaft may be rotated. 85

The brush head is designated by the numeral 22 and is formed preferably of twisted wire having a plurality of bristle tufts secured therebetween, this brush head being of cylindrical form and being disposed within the guard member 12. One end of the stem 23 of the brush head carries a trunnion 24 journaled in a hole in the bearing plate 13 and the other end of the stem has secured thereon a wing member 25 engaged 95 within a transverse recess in the reduced end 17 of the drive shaft 16.

The different parts of the brush are assembled as follows: The brush head 22 is disposed within the guard member 12 with its trunnion 24 extending through the hole in the end bearing plate 13, the drive shaft 16 is inserted through the open end of the casing 10 and its reduced end 17 passed through the hole 15 in the partition 14, the slot or recess 26 in the reduced end 17 of the shaft is engaged upon the wing member 25 carried by the stem of the brush head 22, after which the plug 20 is slid over the crank handle 21 onto the reduced portion 110

18 of the drive shaft and threaded into the open end of the casing 10. In the use of the device, the operator places the guard portion 12 within his mouth with the closed side 5 of the guard disposed against his cheek and with the brush head 22 disposed against his teeth. Holding the casing 10 in one hand the operator grasps the crank handle 21 in the other hand and rotates 10 the drive shaft 16 and consequently the brush head 22 so as to effect a cleansing action on the teeth. The direction of rotation should be such that the brush will rotate away from the gums so as to brush 15 off particles of food and the like away from the gum.

Whenever it is desired to remove the brush head for cleaning or replacing the same, it is merely necessary that the plug 20 20 be unscrewed whereupon the shaft 16 may be moved longitudinally so that it may be disengaged from the wing member 25 carried by the brush head, whereupon the brush head may have its trunnion 24 disengaged from the end bearing plate 13 and consequently removed.

From the foregoing description and a study of the drawing it will be apparent that I have thus provided an extremely 30 simple and efficient rotary tooth brush whereby a cleansing action may be effected longitudinally of the teeth instead of transversely thereof so as to remove all particles of food or other matter from between the 35 teeth and leave the mouth in a highly sanitary and satisfactory condition. It will be furthermore noted that the device may be very easily dis-assembled in order to facilitate cleaning of the parts or in order to 40 replace the brush after the brush has become worn.

While I have shown and described the preferred embodiment of the invention, it will of course be readily understood that I 45 reserve the right to make such changes in the form, construction and arrangement of

parts as will not depart from the spirit of the invention nor the scope of the subjoined claims.

Having thus described my invention I 50 claim:

1. A rotary tooth brush comprising a cylindrical casing having one end open and internally threaded, a portion of said casing being cut away adjacent one end to 55 provide a substantially semi-cylindrical guard member, a bearing plate at the free end of said guard member, a partition within said casing adjacent said cut away portion and provided with a central hole, a 60 drive shaft disposed within said casing and having one end portion reduced and journaled through the hole in said partition, a reduced portion formed on said drive shaft adjacent its other end, a plug threaded with- 65 in the internally threaded open end of said casing and provided with a central opening engaging upon said second named reduced portion, a crank handle formed on the outer end of said shaft, and a brush head disposed within said guard member, connected with said drive shaft and journaled in said bearing plate.

2. A rotary tooth brush comprising a cylindrical casing serving as a handle and 75 provided adjacent one end with a cut out portion, the free end of said casing adjacent said cut out portion being formed as a bearing plate, a drive shaft journaled in said casing and having its end adjacent said cut 80 out portion provided with a central hole and lateral slots communicating therewith, a brush head having its spindle journaled at one end in said bearing plate, and a wing member on the other end of said spindle 85 conformingly engaging within the hole and slot in said drive shaft, and means to permit longitudinal movement of said drive shaft whereby to effect disengagement there- 90 of from said wing member.

In testimony whereof I affix my signature.
CHARLES ABEL, LIEUT. COLONEL.
